D.N.B. Coffin, Jr.

United States Patent Office.

DAVID N. B. COFFIN, JR., OF BOSTON, MASSACHUSETTS, ASSIGNOR TO HIMSELF AND IRAH D. SPAULDING, OF THE SAME PLACE.

Letters Patent No. 66,299, dated July 2, 1867.

IMPROVED CAPSTAN.

The Schedule referred to in these Letters Patent and making part of the same.

TO ALL WHOM IT MAY CONCERN:

Be it known that I, DAVID N. B. COFFIN, Jr., of Boston, in the county of Suffolk, and Newton, in the county of Middlesex, and State of Massachusetts, have invented certain new and useful improvements in Capstans and Windlasses, of which the following is a full and exact description, reference being had to the accompanying drawings, and to the letters of reference marked thereon. With reference to the drawings—

Figure 1 is a general sectional elevation of a capstan on the upper deck, connected on the plan of my improvement patented in 1866, with vertical windlasses on the lower deck.

Figure 2 is a perspective view, showing one of the many ways of applying my present improvement, viz., interposing an elastic element between the parts bearing the pawl-pockets and the barrel to relieve the suddenness of the stress on the pawls and parts operated on by them.

Figure 3 is a transverse section through the barrel, side-shafts, journal-rollers, and spindle, illustrating my improved journal-roller arrangement, which is applicable both to the geared and the simple capstans.

Figure 4 is a sectional perspective view of the fulcrum-gear, showing not only the inclined-surfaced lugs of my 1866 patent, but also the adjacent inclines *x*, which form the subject of one feature of my present improvements.

Figure 5 is a view of the same, illustrating the arrangement of the bolt, said inclines, and their operation, &c.

Figure 6 shows one of the several modes of applying my improvement, in jointing the pawls by casting process alone, to the capstan-barrel or windlass.

Figure 7 shows a modification of the retaining device in the same.

Figure 8 shows another, in which the journal part is cast on the pawl instead of the barrel, and the socket in the barrel.

Figure 9 is still another modification of this improvement in the application of pawls.

Figure 10 shows the centre first moving gear of a capstan, illustrating my improvement, viz., casting or otherwise forming lugs or a clutch on it to automatically clutch or lock into a corresponding clutch or lugs cast or otherwise formed in the lever-head whenever the head is put on.

Figure 11 shows a method of operating the locking-bolts of a capstan, which is further illustrated in the base of the lower part of fig. 1. My improvement in this point will allow the bolts to lock automatically in either direction, at pleasure, or in neither, and to slide over automatically in the direction opposite to that in which it locks.

Figure 12 shows my improved mode of conducting the cable or line clear of the incoming portion.

Figure 13 shows the automatic clutching arrangement between the head and barrel in the case of a simple or ungeared capstan.

Figure 14 shows, together with Figure 19, a mode of automatically locking together the part carrying the pawl-pockets and the bed-plate, so as to leave them free to move somewhat about their centre, subject to an elastic resistance with reference to each other.

Figure 15, another mode of locking the same.

Figure 16 is a plan, and

Figure 17 a sectional elevation of another plan of locking the same parts.

Figure 18 shows a method of securing both parts under the same conditions by means of the bolts which secure the bed-plate to the deck or other foundation.

Figure 20 illustrates my improvement in applying a differential windlass to strain and relieve the friction-band for controlling the windlass in giving out or paying out cable or line, and applicable to both a vertical and a horizontal windlass.

Figure 21 shows another arrangement of the same improvement, and also a bearer between the shaft and friction-wheel in the shape of, or nature of, a bearing for the shaft, and brake-shoe for the friction-wheel, and combined in one.

Figures 22 and 23 are two views illustrating my improvement in the mode of locking and unlocking the

several barrels to and from the friction-wheel, or to and from each other, as the case may be. Another mode, or modification of the mode, is shown in fig. 1, lower-deck windlass.

Like letters refer to similar, like, or corresponding parts in all the figures.

A is the windlass or capstan-barrel, and has cast to it the wrists or journals *a*, with retaining heads *b*; or the journal *a* may be on the pawl. A socket, *c*, is cast in the pawl or in the barrel. This socket has a retainer for the pawl, (see *d*.) The pawl is applied in a position parallel to the axis; and when the capstan-barrel is brought down to its proper position, the pawl, being turned up, cannot get down, and consequently cannot come off, as the downward and parallel position is the only one where it can be applied or removed, (see figs. 1, 6, 8, and 9.) Fig. 7 shows it adapted to be applied or removed in either the upward or downward positions. The pawls can be thrown and operated in either direction, to the right or left. The pawls are arranged to play in pockets, formed of a circular or annular groove, divided by the stops or bridges *e*, against which the pawls act. The spaces in the groove between these bridges *e* are the pawl-pockets, and have a curved section at their bottom. This curved bottom not only gives symmetry and beauty to the design, but serves to direct the pawl as it presses down in action to its centre or deepest point, and so avoids any side strain against the rims of the pockets. It also conveys the water more readily to the outlets in its bottom. In the base of barrel *B* are arranged the sliding-bolts *f*, which act as pawls to detain or lock barrel *B* with reference to bed-plate *C*. In barrel *B* these bolts, one, two, or more, are enclosed from view, but for the side openings *g* made to give access to them. Through these side openings they may be seen and lifted or pried up or down by means of a notch in the side of the bolt for that purpose. Lock-notches *h*, figs. 1 and 11, are formed on the bed-plate by casting or otherwise; and beside them are arranged the inclined lifters *i*, two and two, sloping in opposite directions or reverse order, with a flat elevation, *j*, between. When the elevation *j* is against the lock-notch *h* the bolts may slide freely over them; but when one set of inclines, as in fig. 11, is made to match one set of angles the bolts may slide down and catch when moving in one direction, while they will slide up and over in going to the opposite direction. So if the other reversed inclines are placed to match the other angle the reverse of these latter results occurs. These inclines are connected together and are operated by means of a mover, *k*. To connect and disconnect the barrels *B* and *D* to and from the friction-wheel *E*, which is arranged between them, I form by casting or otherwise a slanting socket and bolt, *l*, the slanting or inclined socket having a counterpart, or socket or shoulder, in the adjacent barrel or wheel, as *m*. The bolt is movable radially, and on being drawn is thrown into socket or between shoulders *m*, and the two parts are locked. On being pushed back toward the centre again they are released, as shown fig. 1; or the device may be modified or changed to that shown in figs. 22 and 23, where the bolt *n* is made to slide radially in a retaining groove in part *D*, and when pressed toward the centre moves in a recess in *E*; but when drawn radially locks against shoulder *o*, when *D* and *E* are thereby become locked together. When pressed toward the centre again in recess *p* the parts *D* and *E* are again free to move independent of each other, recess *p* being a continuous or annular one. A sheave or roller, *q*, is arranged with its axis obliquely to the axis of a capstan or windlass, so as to conduct the delivered cable or line to one side of the incoming portion, (see fig. 12.) When the delivered portion is from the top the red lines represent it; when from the bottom, the black lines. In fig. 1 and fig. 3 is shown a series of rollers, *r*, arranged around the spindle and within the barrel. When these are used the part of the spindle on which they bear, and the part of the barrel on which they bear, as well as the rollers themselves, may all be of unfinished cast metal. The rollers may be conical, as shown, or cylindrical. The rollers may be cast hollow or solid. A shoulder, *s*, in the barrel bears on one end of the rollers, while the other end of the rollers bears on shoulders *t* on the spindle or bed-plate. The endwise thrust may, however, be taken otherwise than on the rollers, if preferred. Fig. 1 (upper deck) shows the fulcrum-gear *F*, furnished with sockets to receive the bolts for locking the gear. Under these bolts *u* is arranged a ring, *v*, for lifting them and holding them up when not required to take on the lugs *w* on the bed-plate. Inclined lifters are formed on the under side of this ring *v* for lifting it, or on the ring *x*, as in other cases, the ring *v* being prevented from turning by notches or shoulders against the stationary guide *y*. In fig. 2 *G* are springs or elastic substance interposed between any suitable part on the stationary portion of the bed-plate and that part, *H*, divided or separate from it, and bearing the pawl-pockets and suitably-formed parts thereon, to be acted on by said elastic substance or springs *G*. Part *H* may be held to the fixed part *L* in any suitable manner to allow it to move somewhat, under control of the resisting spring or elastic substance *G*. Several modes are shown. In lever-head *M* is cast a clutch corresponding to that shown on the centre-gear in fig. 10 and fig. 1, so that when the lever-head is slipped down to its place on the spindle the gear is thereby automatically clutched to it. Concentric or annular flanges or ribs are cast on the bed-plates of the capstans and windlasses, (see fig. 1,) *N*. These flanges *N* give all necessary strength, with some elasticity, and without the liability of fracture, so common to the radial flanges in common use. A small windlass-barrel, *P*, with two sizes of winding surfaces, is arranged to receive connections from the two ends of a friction-strap or band, *Q*, so that by turning the crank or other attachment the differential action furnishes a powerful and easily-managed strain upon the friction-barrel *D* through strap *Q*, which may also be easily relieved by turning in the opposite direction. *R* is a bearing for shaft *P* or *T*, and at the same time a friction-shoe for the friction-wheel *E* or *D'*. In the chain-wheel *B* are formed radial sockets, below the bottom of the groove, and extending up its sides. In these sockets are arranged the chain-lugs *U*, spanning the groove, and made adjustable radially, to fit different chains. They may be adjusted by putting blocks behind them, or by means of the keys *z*, shown. These keys may be straight, or conform to an annular groove in the throat of the wheel; or these chain-lugs may be adjusted radially and held by screws.

Having described my improvements, what I claim as my invention, and desire to secure by Letters Patent is as follows:

1. The application of pawls to a capstan by means of a cast joint or hinge, in any manner so as to allow the pawl to operate in both directions.
2. The employment of a side opening, *g*, in combination with the enclosed bolt, in the construction of a capstan.
3. The arrangement of inclined lifters, made movable, in combination with the lock-notches or spaces *h*, so as to be used both to slide the bolts out of connection automatically, and also at the pleasure of the operator.
4. The arrangement of inclined lifters *i* in duplicate and in reverse order, in combination with lock-notches or lugs and sliding-bolts.
5. The arrangement of an elevated flat part, *j*, between two inclines, arranged in reverse order, substantially as and for the purpose set forth.
6. Radially-sliding keys or bolts, in combination with a retaining socket in one part, and a locking space or shoulder in another of two parts of a capstan or windlass, to be connected and disconnected, substantially as described.
7. A roller or sheave, arranged, with its axis, obliquely to the windlass and its axis, substantially as described.
8. The employment of conical or cylindrical rollers, arranged in combination with the spindle and barrel of a capstan or windlass, to relieve the friction incident to the side or transverse thrust, substantially as described.
9. The arrangement of rollers longitudinally between the shoulder of the barrel and that of the spindle or bed-plate, to sustain or support the barrel endwise.
10. The arrangement of sliding-bolts in sockets on the fulcrum-gear, as described.
11. The lifting and sustaining ring *v*, in combination with the bolts or locking mechanism of a capstan and inclined lifters, arranged either on it or an auxiliary part, *x*.
12. The employment of an elastic or spring element interposed between the part bearing the pawl-pockets and the fixed portion of the bed-plate.
13. The inclines *X*, for automatically lifting the fulcrum-gear, substantially as shown.
14. Locking or clutching the centre or first moving gear of a capstan to the lever-head automatically by interlocking lugs formed on each, substantially as described.
15. The arrangement of a concentric, circular, or annular flange or rib, or flanges or ribs, *N*, between the spindle or hub and the rim or periphery of the bed-plate of a capstan or windlass, substantially as described.
16. The arrangement of a friction-wheel between the two barrels of a capstan or windlass, with provision for connecting or disconnecting it to or from one or both, at pleasure.
17. The application of the differential windlass to the friction mechanism of a capstan or windlass.
18. The employment of the combined bearing and brake or friction-shoe in the friction mechanism of a capstan or windlass.
19. The employment of chain-lugs, spanning the groove in the chain-wheel, and made adjustable radially in sockets at the bottom, and extending up the sides of the groove between the two cheeks of the chain-wheel, substantially as described.
20. The employment of keys back of said lugs, with or without the circular form, substantially as described.
